UNITED STATES PATENT OFFICE.

AMBROSE WILLIS, OF TROY, NEW YORK.

FLY-ESCAPE FOR WINDOW AND DOOR SCREENS.

SPECIFICATION forming part of Letters Patent No. 341,087, dated May 4, 1886.

Application filed August 21, 1885. Serial No. 174,966. (No model.)

To all whom it may concern:

Be it known that I, AMBROSE WILLIS, of the city of Troy, county of Rensselaer, State of New York, have invented new and useful Improvements in Fly-Escapes for Window and 5 Door Screens, of which the following is a specification.

My invention relates to certain improvements in door and window screens, for inducing the escape of flies from the room wherein the doors or windows containing the screens are placed.

My invention consists (as will be more fully detailed hereinafter in connection with its 15 illustration) in the combination, with the screen proper of a door or window, of an apron or curtain that is made of a similar material to the screen, and is arranged on what is the inner face of the latter relatively to the room in which the screen is placed, said apron or curtain being downwardly extended from the top of the screen at a sufficient distance therefrom to allow the flies to crawl up between said curtain or apron and screen, either the screen 20 proper or the curtain or apron having concavities of an upward-tapering form, while the screen and the apron or curtain are connected at the edges of said concavities to form inclosures thereat, and openings are provided 25 in the screen proper at or near the top of the inclosures for the outward escape of the flies.

Accompanying this specification, to form a part of it, there are two plates of drawings 30 containing ten figures illustrating my invention, with the same designation of parts by letter-reference used in all of them.

Of these illustrations, Figure 1 shows the top portion of a door or window screen, which is illustrated as having concavities formed 35 therein, the walls of which converge, which taper upwardly, and are provided with escape-openings at or near the top. Fig. 2 shows the form of apron or curtain used when the concavities are made in the screen proper, the curtain 40 being shown as separated from the screen in this figure. Fig. 3 shows the screen illustrated at Fig. 1 and the curtain shown at Fig. 2 as connected to produce my invention. Fig. 4 shows a section taken on the line $x^1 x^1$ of Fig. 3, and 45 Fig. 5 shows a section taken on the line $x^2 x^2$ of Fig. 3. Fig. 6 shows the top part of a door or window screen adapted to produce a modi-

fication of my invention, and Fig. 7 shows a curtain having the concavities made in the latter instead of in the screen proper, as they 55 are shown at Fig. 3. Fig. 8 illustrates the screen shown at Fig. 6 and the curtain appearing at Fig. 7 as connected to produce a modification of my invention. Fig. 9 is a section taken on the line $x^3 x^3$ of Fig. 8, and Fig. 60 10 is a section taken on the line $x^4 x^4$ of Fig. 8.

The several parts of the apparatus thus illustrated are designated by letter-reference, and the function of the parts is described as follows: The letter S designates the screen 65 proper, which is of the usual form, made in one piece from wire-cloth, and at its edges secured in the frame F. The letter A designates the curtain or apron, which is also secured on all of its edges but the lower one in 70 the frame F. This apron and screen are arranged to be in contact with each other, excepting where either is bent outwardly and laterally to form concavities C', which may be made either in the screen proper or the curtain A. These concavities, when the screen proper and curtain are connected so as to be in contact at the edges of the concavities, produce the inclosures E. These inclosures E are 75 open at the bottom, and are between the screen proper and apron, above the bottom of the latter, with the apron far enough away from the screen proper thereat for the flies to crawl upwardly within the passage-way a between the two to enter the inclosures E. The sides of 80 the inclosures taper inwardly and upwardly to a point, P, and immediately opposite the latter there are formed in the screen proper egress-passages O, which open outwardly. At 85 the side of the inclosures E the screen proper and the curtain part are in contact.

The operation of the parts thus made is as follows: Flies that are inside of the room wherein the window or door screens are, being attracted by the incoming light from the 90 screen, gather upon the inner surface of the latter, and, as they generally will under such conditions crawl upwardly, they pass under the lower end of the apron or curtain A into the passage a, whereat they enter the inclosures E, to escape from which they crawl out 95 from the openings O, and are thus induced to leave the room.

I am aware that a screen for a like purpose

has been patented, in which a series of strips were transversely arranged in a frame with their lower edges downwardly overlapping on the apartment-face of the screen and containing where thus overlapping V-form pieces of wire that were placed between the overlapping and underlapping edges of the strips to produce escape-passages for the flies. The transverse division of the screen into several parts increases the tendency of the screen to sag when applied to windows that rise and fall to open and close, and to bag out and stretch when applied to doors that close with some force, and hence much better conditions of use are had by my improvement, where the screen proper is in one piece with the apron in contact with it except where the concavities are bent to produce the inclosures for the escape of flies.

I am aware that a door-screen has been patented which was made with an opening cut across the whole width of the screen at the top, with an apron or curtain hung down from the top of the frame at a sufficient distance from the screen proper to leave a space for the passage of the flies up to the top opening. This older construction left the screen proper unconnected at the top, and while flies will enter a large opening leading into an inclos-

ure, they will not enter a small one; hence 30 with a large opening at the top, such as extended across the face of the screen, the invitation to come in would be about as strong as the suggestion to go out.

Having thus described my invention, what I 35 claim, and desire to secure by Letters Patent, is—

The combination of the screen S, made in one piece, having the egress-openings O produced therein, and being attached at its sides, 40 top, and bottom to a supporting-frame, the apron A, made of screen material, and being also attached at its sides and top to said frame, the inclosures E, having the entrance-openings a, and produced between the said screen 45 proper and apron by bending away from their contact the said screen or apron, said inclosures being arranged with reference to the egress-openings O, substantially as and for the purposes set forth.

Signed at Troy, New York, this 19th day of August, 1885, and in the presence of the two witnesses whose names are hereto written.

AMBROSE WILLIS.
